UNITED STATES PATENT OFFICE.

THOMAS WRIGHT, OF GRANDVIEW, MANITOBA, CANADA.

MAKINGS-TOBACCO POUCH.

1,389,175.

Specification of Letters Patent. Patented Aug. 30, 1921.

Application filed March 2, 1920. Serial No. 362,856.

To all whom it may concern:

Be it known that I, THOMAS WRIGHT, a subject of the King of Great Britain, residing at Grandview, in the Province of Manitoba and Dominion of Canada, have invented certain new and useful Improvements in Makings - Tobacco Pouches; and I do hereby declare the following to be a full, clear, and exact description of the invention, such as will enable others skilled in the art to which it appertains to make and use the same.

This invention relates to an improved tobacco pouch and more especially to one designed for the use of smokers of cigarettes, the same being so constructed as to securely hold tobacco suitable for use in the preparation of cigarettes and having means for holding and protecting a package of cigarette papers.

An object of the invention is to provide a pouch of leather, rubber, a composite material such as silk and rubber or any other suitable flexible material so constructed as to securely retain the tobacco when folded and carried in the pocket.

Another object is to arrange the pouch in such a manner that when the same is opened or folded back on itself in a position preparatory to making a cigarette, the pocket containing the tobacco and from which the same is to be poured into a cigarette paper, as well as the pocket in which the package of papers is retained, are both freely accessible, yet when the pouch is folded to be carried in the pocket, the tobacco pocket is securely closed and effectually retained in said position due to the fact that the closure flap for said tobacco pocket is arranged at the doubling line of the pouch, and is thereby securely retained in position to prevent the escape of any tobacco from the tobacco pocket even though the sides of the pouch are bulged out through handling or when a large quantity of tobacco is in the pocket.

Another object is to provide a reinforcement of the pouch at a point subject to greatest wear, or at its doubling edge, such reinforcing member acting as a closure for the tobacco pocket.

Again this improved construction provides not only for the free accessibility of the cigarette papers when needed but the pockets are so arranged that when the pouch is opened or doubled back upon itself for use, both the tobacco pocket and the cigarette paper packet are in a position to retain their contents effectively.

Further said arrangement of parts provides that when the pouch is closed and carried in the pocket of the user, the cigarette papers will be inside of the pouch and effectually protected from dampness, dust or other injury incident to the ordinary practice of carrying the paper separately in the user's pocket or on the outer surface of the pouch.

Another object is to provide a cigarette-paper pocket of such a construction as to receive any of the standard paper packages now on the market and one from which the papers may be withdrawn singly without removing the package of papers from its packet. It is noted that one form of paper package involves a peculiar construction and to provide for the accommodation thereof is one of the features of this invention.

These and other objects in view will be obtained by providing such novel features of construction as will be hereinafter more fully described, illustrated in the accompanying drawing and finally claimed.

The preferred embodiment of the invention is presented in the accompanying drawing forming a part of this specification in which similar characters of reference indicate corresponding parts in all the views.

Figure 1 is an elevation of the improved device ready to be inserted in the pocket.

Fig. 2 is a vertical section on line 2—2 of Fig. 1.

Fig. 3 is an elevation of the pouch after it has been opened as when making a cigarette showing the tobacco pocket in elevation.

Fig. 4 is a vertical section on line 4—4 of Fig. 3.

Fig. 5 is an elevation of the pouch with the parts as shown in Fig. 3 and viewed from the opposite side, or showing the cigarette paper containing pocket in elevation,

also showing the cover of the cigarette package thrown back to further illustrate the peculiar formation of the pocket in which the papers are retained.

5 Fig. 6 is a view of the blank used in the construction of the pouch.

Fig. 7 is a view of the blank used in the construction of the cigarette paper pocket.

10 Fig. 8 is a similar view of the closure flap 10 of the tobacco pocket before it is sewed into position near the doubling line of the pouch.

Referring now to the drawings by numerals it will be seen that the pouch is made up of a tobacco pocket 1 formed by doubling 15 a part of the blank on itself and stitching at 2—2, thus forming a receptacle or compartment in which tobacco may be held. Said pocket 1 is closed on three sides and is open along its fourth as at 3.

20 A closure flap 4 shown at 5 stitched or secured in any other preferred manner to the body portion of the pouch, is so located as to double over and effectually close the open or unsecured edge or mouth of the tobacco pouch.

As will be seen the formation of the tobacco pocket utilizes approximately two-thirds of the length of the blank and the remaining one-third as seen at 6 has secured 30 to its inner face the cigarette paper carrying pocket 7.

The portion 6 of the blank is adapted to be folded down over the doubled portion forming the tobacco pocket and to be secured 35 preferably by glove fasteners or the like having their male members mounted near the lower outer corners of the tobacco pocket and the female members mounted in the folding member 6.

40 The tobacco pocket closure flap 4 is preferably sewed as at 5 close to the doubling line 10 of the pouch and has the doubling line 9 corresponding and registering with the doubling line 10 of the pouch. By this 45 construction when the portion 6 of the pouch is doubled over the closure flap 4 said flap is caused to bend sharply or abruptly over the mouth of the tobacco pocket and thereby effectually close said pocket and prevent 50 any tobacco escaping until the folding member 6 is unsnapped and fully thrown back. By providing the closure flap in the position shown it acts as a reinforcement to the pouch at a point that would ordinarily 55 deteriorate most rapidly.

The cigarette paper package containing pocket 7 may be of the same material as the pouch or any other preferred material and as shown is stitched as at 11 through wings 60 or portions 12 to the inner face of the folding member 6.

The pocket 7 is provided with slits 13 through which certain forms of cigarette papers may project, and is so arranged and

located that the cover of the cigarette paper package may be forced down smoothly over the outer face of the pocket to fully protect that portion of the paper exposed through the slits 13 when the pouch is closed.

It will be noted that the pouch as described 70 is oppositely foldable from a normal or closed position to a reversed or opened position, and vice versa, the tobacco and match pockets both being closed and sealed to prevent the accidental escape of the contents 75 thereof when the pouch is in the normal or closed position and both being exposed to give access to their contents when the pouch is in the reversed or open position. Further 80 it will be observed that the fold line of the pouch serves to effect an abrupt bending of the tobacco pocket closing flap over the open side or edge of said pocket, and when the pouch is in the normal or closed position the free edge of said closing flap is engaged by 85 the paper pocket, or the pocket designed for the reception of the cigarette paper package and is thereby locked securely against displacement such as to permit of the escape 90 of the contents of the tobacco pocket.

Moreover as will be seen, the tobacco and paper receiving and holding pockets have their open edges directed in common toward the fold line of connection between the members of the pouch, which members 95 respectively carry said tobacco and paper holding pocket, so that whether the pouch is in the normal and closed or in the reversed and open position, the open edges of the pockets face in the same direction, and while 100 the tobacco pocket has its open edge arranged close to the fold line between the members of the pouch, the open edge of the paper receiving pocket is set back or removed from said fold line, a sufficient distance to adapt 105 it to serve as an effective securing means for the free inner edge of the cover flap by which the tobacco pocket is primarily closed to confine its contents.

It will be obvious moreover that a pouch 110 constructed as described, while insuring efficiency for the purpose indicated has the advantage of simplicity and of requiring a relatively small amount of material in its construction, and the contents of the same, 115 while readily accessible when the pouch is opened, are entirely protected and securely retained in place when the pouch is closed.

What is claimed is:

A pouch having foldable members, a tobacco receiving pocket carried by one of said members opening in the direction of the fold line of the members and having its opening arranged in close proximity to said fold line, a narrow flap secured at the fold line of said members for closing said pocket and for use as a guide for directing the tobacco into a cigarette paper, a pocket carried 120 125

by the other of said members for the reception of a package of cigarette papers and opening in the direction of the fold line of the members and having its opening spaced 5 slightly from said fold line, said package adapted to engage said flap and thereby securely close said tobacco pocket when the members are in their closed relation, and re-

leasable means for securing said members in such relation. ¹⁰

In testimony whereof I affix my signature in presence of two witnesses.

THOMAS WRIGHT.
